CLAIM

The ornamental design for a combined neck chain and pendants, substantially as shown and described.

DESCRIPTION

FIG. 1 is a rear perspective view of a combined neck chain and pendants showing my new design, the neck chain shown only partially for ease of illustration;

FIG. 2 is a front perspective view thereof;

FIG. 3 is a right side elevational view thereof;

FIG. 4 is a bottom plan view thereof;

FIG. 5 is a top plan view thereof; and

FIG. 6 is a rear perspective view thereof in separated condition.

FIG. 1.**FIG. 2.****FIG. 4.****FIG. 3.****FIG. 5.****FIG. 6.**
